Charles E. Bozarth, Palo Alto, Calif., assignor to Ampex Corporation, Redwood City, Calif., a corporation of California

Filed Mar. 21, 1967, Ser. No. 6,327

Term of patent 14 years

(Cl. D26—14)

FIG. 1

FIG. 2

FIGURE 1 is a front, left side and top perspective view of a television tape transport with the cover open, showing my new design, the top of the cover being conventionally plain, and the right side being a mirror image of the left side; and

FIGURE 2 is a plan view of the transport of FIGURE 1 with the cover removed.

The dominant features of my new design are shown in solid lines in the drawing.

I claim:

The ornamental design for a television tape transport, substantially as shown and described.
